CLAIM

The ornamental design for a gaming machine cabinet, as shown and described.

DESCRIPTION

FIG. 1 is a perspective view of a gaming machine cabinet, showing my new design;

FIG. 2 is a top view thereof;

FIG. 3 is a front elevational view thereof;

FIG. 4 is a right side elevational view thereof; and,

FIG. 5 is a rear elevational view thereof.

Broken lines on FIGS. 1, 3 and 4 indicate disclaimed portions and form no part of the claimed design.

1 Claim, 5 Drawing Sheets
